[57] CLAIM

The ornamental design for a hand-held tool for removing insulation from electrical conductors, as shown and described.

DESCRIPTION

FIG. 1 is a top plan view of a hand-held tool for removing insulation from electrical conductors showing my new design;

FIG. 2 is a side elevation view;

FIG. 3 is an end view;

FIG. 4 is an opposite end view; and

FIG. 5 is a perspective view.

The bottom side as would be seen opposite FIG. 1 is planar and unornamented.
